UNITED STATES PATENT OFFICE.

EDWARD M. COYNE, OF CHATHAM, ONTARIO, CANADA.

SUNSHADE.

1,143,891.

Specification of Letters Patent. Patented June 22, 1915.

Application filed August 4, 1914. Serial No. 855,014.

To all whom it may concern:

Be it known that I, EDWARD M. COYNE, a citizen of the United States, residing at Chatham, in the Province of Ontario and 5 Dominion of Canada, have invented a new and useful Sunshade, of which the following is a specification.

This invention relates to certain new and useful improvements in sun-shades for draft 10 animals.

An object of the present invention is to provide a sun-shade for horses which will be light in weight and therefore thoroughly practicable in use.

15 A further object is to provide an apparatus of the above mentioned class by means of which the sun-shade may be adjustably secured upon the horse's head to thus properly shade and protect the same, regardless 20 of the angle at which the horse carries his head.

25 A further object is to provide a sun-shade so mounted that if it should catch in any obstacle, the shade will be detached from the holding frame so as to thus prevent the destruction of the apparatus and also prevent 30 bruising of the animal's head.

With the foregoing and other objects in view which will appear as the description 35 proceeds, the invention resides in the combination and arrangement of parts and in the details of construction hereinafter described and claimed, it being understood that changes in the precise embodiment of the 40 invention herein disclosed, can be made within the scope of what is claimed, without departing from the spirit of the invention.

In the drawings accompanying this specification and forming a part thereof, the preferred embodiment of my invention is illustrated, wherein:

Figure 1 is a perspective view of the device including the sun-shade proper, and the supporting or bridle frame. Fig. 2 is a view 45 of a somewhat modified form of bridle frame. Fig. 3 is a further modification of the foregoing.

Referring to the drawings in which similar reference numerals designate corresponding parts throughout the several views, the bridle frame 6 includes the two cheek pieces 7 and the forehead member 8. A nose piece 9 extends between the cheek pieces and forehead member and in connection with the ear

member 10 defines a bridle adapted to engage the head of a horse and by reason of the various buckles and straps be rigidly secured thereto. A driving bit may be carried by the bridle frame or a separate bridle may be used in connection with the present frame 55 for the support of the bit, as desired.

The forehead member 8 is formed of some rigid material suitably faced so as to properly protect the animal from contact therewith, which rigidity provides for the proper 60 support of the upstanding projections 11 of which there are three illustrated. The projections 11 are rigidly secured to the forehead member 8 and are arranged along the longitudinal axis thereof whereby the sun-shade proper 12 may be adjustably mounted 65 by the bridle frame and so positioned as to compensate for the obliquity of the sun or the angular position of the animal's head. The projections 11 are externally threaded 70 and therefore capable of receiving thereon and threadedly engaging the socket 13 which constitutes the lower portion of the sun-shade 75 12.

The sun-shade proper includes as mentioned, the socket 13 which is internally threaded at its lower extremity for securement upon the projections. The upper extremity of the socket 13 is provided with a cylindrical bore into which extends the resilient support 14, the same effecting a friction joint therewith such that the sun-shade 80 may be forcibly rotated or forcibly withdrawn but will be normally prevented from accidental displacement or movement. The upper extremity of the center post is provided with the ferrule 15 into which the wire 16 which forms the frame of the shade 85 extends and is secured. The cover of the shade is illustrated in dotted lines as at 17 and may partake of any desired form or include any suitable decorations according to 90 the taste of the purchaser.

A somewhat modified form of bridle frame is illustrated in Fig. 2 in which the 100 various cheek pieces and forehead members are formed of wire, the facing or covering of which has been removed in order to more clearly disclose the wire-like construction of the same. The frame includes an ear member 10' formed integral with the remaining portions of the frame and is of considerable width accomplished by bending the wire 105

into zigzag shape as disclosed. The same method is followed in order to increase the area of the cheek pieces and forehead member at certain points where they contact 5 with the animal's head to thus insure a wide bearing area therewith. The threaded projections 11 are carried by a special plate 18 which is secured to the wire frame and the entire frame as thus constructed is faced 10 with leather or other material so as to present a neat and slight appearance and provides for its efficient and humane use.

The further modification illustrated in Fig. 3, is modified to the extent that the extensions 19 of the arm shown in Fig. 2 and which constitute the lower portions of the cheek pieces and forehead member are omitted in said particular form and the desired engagement or securing to the horse's 20 head is obtained by using the bridle frame in connection with the ordinary driving bridle beneath or above which the former extends and by means of which it is thus held in place.

25 The support 14 which may be composed of a series of rods or a coiled spring, is resilient, to permit the shade to give should the tossing of the horse's head cause the shade to strike a person or obstacle. Where 30 desired, the projections 11 may be sockets to receive the support 14.

Having thus fully described my invention, what I claim is:—

1. An apparatus of the class described, including a bridle frame, threaded projections carried thereby, and a sun-shade including a socket with a lower threaded end adapted to engage any of said projections, a post frictionally engaging said socket, and a shade frame and cover mounted upon the 40 upper extremity of said post.

2. An apparatus of the class described, comprising a bridle frame including cheek pieces and a forehead member, means for securing the same to an animal's head, a 45 series of attaching means carried by and arranged in an axial row upon the said forehead member, a bracket with a socket adapted to detachably engage any of said attaching means, a center post frictionally engaging said socket, a ferrule carried at the upper extremity of said center post, a wire frame carried by said ferrule and post, and a cover carried by said wire frame for shading and protecting an animal's head. 50

In testimony that I claim the foregoing as my own, I have hereto affixed my signature in the presence of two witnesses.

EDWARD M. COYNE.
